(57) **CLAIM**

The ornamental design for a knife sharpener as shown and described herein.

DESCRIPTION

FIG. 1 is a front top quarter perspective of a knife sharpener showing the new design, wherein a cap is positioned at the top;

FIG. 2 is a rear bottom quarter view of the design in FIG. 1; FIG. 3 is a first side view of the design in FIG. 1;

FIG. 4 is a front view of the design in FIG. 1;

FIG. 5 is a rear view of the design in FIG. 1;

FIG. 6 is a second side view of the design in FIG. 1;

FIG. 7 is a top view of the design in FIG. 1;

FIG. 8 is a bottom view of the design in FIG. 1;

FIG. 9 is a front top quarter perspective of a knife sharpener of FIGS. 1 through 8; except that the cap is removed;

FIG. 10 is a rear bottom quarter view of FIG. 9;

FIG. 11 is a first side view of the design in FIG. 9;

FIG. 12 is a front view of the design in FIG. 9;

FIG. 13 is a rear view of the design in FIG. 9;

FIG. 14 is a second side view of the design in FIG. 9;

FIG. 15 is a top view of the design in FIG. 9; and,

FIG. 16 is a bottom view of the design in FIG. 9.
